UNITED STATES PATENT OFFICE.

LAZENBY C. HAMLINK, OF CLEVELAND, OHIO, ASSIGNOR TO THE GAS MACHINERY COMPANY, OF CLEVELAND, OHIO, A CORPORATION OF OHIO.

MUFFLE-FURNACE.

1,081,960.

Specification of Letters Patent. Patented Dec. 23, 1913.

Application filed October 9, 1911, Serial No. 653,692. Renewed October 13, 1913. Serial No. 794,996.

To all whom it may concern:

Be it known that I, LAZENBY C. HAMLINK, a citizen of the United States, resident of Cleveland, county of Cuyahoga, and State of Ohio, have invented a new and useful Improvement in Muffle-Furnaces, of which the following is a specification, the principle of the invention being herein explained and the best mode in which I have contemplated applying that principle, so as to distinguish it from other inventions.

My invention, while having general reference as entitled, to a muffle-furnace, relates particularly to the form of furnace construction, and is still more specifically directed to the relative disposition of partitions and distributing flues.

The object of this invention is the provision of an apparatus which shall combine with economy of construction, a measurably increased economy of operation.

The said invention consists of means which are hereinafter fully described and particularly pointed out in the claims.

The annexed drawing and the following description set forth in detail certain mechanism embodying the invention, the disclosed means, however, constituting but one of various mechanical forms in which the principle of the invention may be applied.

Referring to the drawing, Figure 1 represents a vertical section of an apparatus embodying my invention. Fig. 2 is a horizontal section on line II—II of Fig. 1, looking in the direction of the arrows.

The figures represent in the main, as regards exterior outline, the approved modern-day type of muffle-furnace adapted for use in connection with gas-producing apparatus. So much only will be described as pertains to the essence of this invention and as will serve to afford a ready understanding of the operation. As already stated, the elemental features consist in an arrangement of oven partitions and intermediary flues such that the desired results may be effected.

Referring to Fig. 1, a gas generator is designated by the reference letter A, and includes in its lower construction a furnace comprising a grate a' and fire-door a'' . At the top of the generator a suitable charging opening a^3 is provided. The casing B is located some distance above the bottom of the generator, as is usual, in order to permit dumping conveyances to be moved

underneath. In the oven B, a plurality of retorts C, (in this instance eight) are represented. These retorts, as shown, may be arranged in two rows of four each, running parallel with the wall interposed between the oven and the generator, as clearly appearing in Fig. 2. All the retorts extend vertically the entire height of the casing, and are provided above and below with suitable charging and dumping appliances, not shown. It has generally been found best to connect the two rows of retorts through the medium of stiffening studs c' , and also with the inner walls of the casing. The casing B, in accordance with the illustrated form of my invention, is first divided in half by the substantially horizontal partition b' , to form upper and lower heating chambers having no direct communication with each other whatever. Each of these chambers is then again divided in half by two horizontal members b^2 b^2 serving as baffle-plates, which are, however, each provided with four openings designated as b^3 . These openings are located as most clearly shown in Fig. 2, between that inner vertical wall b^4 of the casing farthest removed from the generator, and the outer sides of the four respectively adjacent retorts. Heretofore these heating chambers have been connected with each other in series forming a single passage for the gases of combustion, but by my improved construction it will be noted, as will hereinafter appear, that this passage or course is divided into distinct and separate passages. Depending from each of these plates b^2 , and positioned immediately beneath the openings b^3 , are two bag-walls each designated as b^5 . These bag-walls b^5 may be, as shown, of greater cross-sectional area than the openings b^3 , such that they may be firmly fitted between the inner wall b^4 and the particular retort adjacent thereto, and should furthermore extend somewhat nearer the bottom of the two chambers. As will now be evident, any gaseous mixture intended to reach the upper division of the heating chambers through the openings b^3 is, after naturally rising in the lower divisions, drawn downwardly to permit of its passage through these walls and on into the upper divisions. It is this momentary retention of the gases, due to the sinuous course they are in such wise compelled to take, which is calculated

to more uniformly apply the heat. All the partitions just mentioned may be secured in any approved manner either to the sides of the casing, or to the sides of the retorts, as may prove most feasible.

Referring now to the wall between the generator and the casing B, it will be noted that an upright flue D is provided having direct communication with the furnace 10 through the main inlet d' . This upright flue communicates through horizontal gas channels d^2 d^2 , somewhere near the bottom, with the lower division of each of the chambers. Located immediately above the channels d^2 15 d^2 , and in fact in substantial opposition thereto, are the air-inlets d^3 d^3 . These may have their intake at any part of the apparatus that may be chosen, as will be readily understood. The intermediary wall between 20 the generator and casing B is also provided near the top of each of the two upper divisions with outlet openings d^4 d^4 , to permit the exit of the waste gases prior to their arrival at the recuperator.

25 Considering the operation of the apparatus as a whole, it will be apparent that the producer gas will rise through the main inlet d' , to pass into the lower division of the lower chamber through the channel d^2 , and 30 also, after passing through the upright flue D, through the upper channel d^2 , and almost immediately thereafter each of these currents will meet and become mixed with the incoming supply of air through the openings d^3 d^3 . As should be obvious, the draft set up at each of the inlets d^2 and d^3 respectively, is such as will occasion a swirling, effecting at one and the same time a better combustion and a more thorough dissemination 35 of heat throughout that particular division of the heating chamber prior to the passage of the gases up between the bag-walls b^5 on their course to the outlets d^4 . It is this indirect resistance and deflection of 40 the gases downwardly by the bag-walls to the strong draft likely to be set up in an apparatus of this character which has been discovered actually detains the heat a sufficiently longer period of time to more uniformly 45 heat the lower portions of the retorts in each heating chamber, and hence as a direct result, to add that measure of increased efficiency which is sought. Furthermore, by dividing the course of the gases of 50 combustion, and thereby shortening such course, a less velocity may be imparted thereto for the purpose of exhausting them, than when such course is longer. This condition further contributes to the increased 55 heating capacity of such gases, inasmuch as they remain in contact with the retorts a correspondingly increased time, and furthermore permits the gases to be better controlled, since it is possible by this construction to regulate the temperature in either 60 65

section to be increased or diminished independently of the other, an independent damper, not shown, being provided for each waste duct.

Having fully described my invention, 70 what I claim and desire to secure by Letters Patent is:—

1. In a muffle furnace the combination of a generator; a casing; one or more vertical retorts within said casing; a partition forming superimposed and independent heating chambers within said casing; each chamber being provided with a horizontal plate dividing same into upper and lower compartments; the lower compartment of each 75 chamber provided with an air inlet and the upper compartment of each chamber with a gas outlet; said plate being provided with means forming the sole gas inlet for the upper chamber; and a gas inlet establishing communication between said generator and lower compartment of each chamber. 80

2. In a muffle furnace the combination of a generator; a casing; one or more vertical retorts within said casing; a partition forming super-imposed and independent heating chambers within said casing; each such chamber being provided with a horizontal baffle plate dividing each chamber into two compartments, and means therethrough 90 establishing communication between same, said means being placed in the end of said plate opposite that which is adjacent to said furnace and forming an outlet for the lower compartment; a gas inlet establishing communication between said furnace and lower compartment of each chamber and a gas outlet leading from the upper compartment of each chamber into a suitable flue; said partition forming the sole inlet for said upper 95 chamber. 100

3. A muffle-furnace comprising the combination of a generator; a casing; a wall interposed between said generator and casing; one or more vertical retorts within said 110 casing; a partition extending horizontally across said casing and forming superimposed and independent heating chambers; a plurality of substantially horizontal plates, each provided with an opening and disposed on opposite sides of said partition, said openings being remotely located relative to 115 said wall, and means comprising flues within said wall for simultaneously conducting gases to and from opposite sides of said 120 plates. 125

4. A muffle-furnace comprising the combination of a generator; a casing; one or more vertical retorts within said casing; a substantially horizontal partition in said casing tightly inclosing said retorts and forming superimposed and independent heating chambers; a plurality of substantially horizontal baffle-plates, each having an opening and disposed on opposite sides of 130

said partition; and a wall interposed between said generator and casing, said openings being located adjacent the opposite wall of the latter, said interposed wall being provided with an upright flue communicating with said heating chambers diagonally below each such opening, and with said generator, said wall further provided with outlet openings communicating with said chambers diagonally above each such opening.

5. In a muffle furnace the combination of a generator; a casing; one or more retorts extending vertically within said casing; the latter forming a heating chamber around 15 said retorts; a horizontal plate within said casing forming independent heating chambers divided into upper and lower compartments; an inlet establishing communication between said furnace and one end of the 20 lower compartment; and an outlet leading from the upper compartment into a suitable flue; said plate being provided with opening means therethrough forming the outlet from the lower chamber the sole inlet for the 25 upper chamber; said means being placed in that end of said plate which is opposite that end adjacent to the said first named gas inlet.

6. A muffle-furnace comprising the combination of a generator; a casing; one or 30 more upright retorts intersecting the interior of said casing; a closed, substantially horizontal partition within said casing intersected by said retorts and forming independent heating chambers; substantially horizontal baffle-plates extending across said 35 chambers and positioned on opposite sides of said partition, each such plate having an opening; bag-walls depending below said 40 openings and affording sole communication therethrough; and means for conducting gases to and from both sides of said plates.

7. A muffle-furnace comprising the combination of a generator; a casing having 45 an upright wall integral with said generator; one or more upright retorts extending through the interior of said casing; a closed, substantially horizontal partition dividing said casing and intersected by said 50 retorts and forming independent heating chambers; substantially horizontal baffle-plates extending across said chamber on opposite sides of said partition and intersected by said retorts, each of said plates having an

opening adjacent the opposite wall of said 55 casing, said integral wall being provided with flues adapted to establish communication between said generator and corresponding sides of said plates; said wall being further provided with outlet flues communicating with said chambers on correspondingly opposite sides of said plates.

8. A muffle-furnace comprising the combination of a generator; a casing having one 60 upright wall integral therewith; one or more upright retorts extending through the interior of said casing; a closed, substantially horizontal partition extending across said interior, intersected by said retorts, and forming independent heating chambers; substantially horizontal plates extending across 65 said chambers and positioned on opposite sides of said partition, said plates being similarly intersected by said retorts and provided each with an opening adjacent the 70 opposite wall of said casing; a bag-wall depending below and inclosing each such opening, said integral wall being provided with an upwardly extending flue communicating with said generator and with said chamber 75 below said bag-walls, said integral wall being further provided with outlet and air inlet flues communicating with said chambers respectively above and below said 80 plates.

9. In a muffle furnace the combination of a generator; a casing; one or more retorts extending vertically within said casing; the latter forming a heating chamber around 85 said retorts; a horizontal plate forming independent heating chambers divided into an upper and lower compartment; a gas inlet establishing communication between that end of the lower compartment near said furnace and the latter; and a gas outlet leading 90 from the similar end of the upper compartment to a suitable flue; said plate being provided with opening means establishing communication between the upper and lower compartments and at the opposite ends of 95 the latter and forming an outlet for the lower chamber.

Signed by me, this 18th day of September, 1911.

L. C. HAMLINK.
